PETER THOMSEN, OF CASSEL, GERMANY, ASSIGNOR TO SCHMIDT'SCHE HEISSDAMPF-
GESELLSCHAFT M. B. H., OF CASSEL-WILHELMSHOHE, GERMANY, A CORPORATION
OF GERMANY.

WATER-TUBE BOILER.

Application filed January 2, 1923. Serial No. 610,227.

To all whom it may concern:

Be it known that I, PETER THOMSEN, a citizen of Germany, and resident of Cassel, Germany, have invented certain new and useful Improvements in Water-Tube Boilers, of which the following is a specification.

This invention relates to water tube boilers and particularly to those of the Yarrow type, comprising a superheater and three drums, one upper one and two lower ones, the latter being connected with the upper drum by substantially straight tubes. The object of my present invention is to provide an arrangement which will enable the superheating action to be regulated as required at different times.

The particular features by which I attain this object will now be described in connection with the accompanying drawing, which is a vertical section showing as an example a typical form of my invention.

At *a* I have indicated the upper drum of the boiler which is connected with the semi-cylindrical water drums *b* located at the bottom by straight inclined tubes *c*. The furnace gases coming from the space located between said lower drums *b* are directed to hot gas flues located at each side of the boiler, and these flues are shown divided into two upwardly extending branches or ducts *d e* respectively by means of an upright partition *f*, the lower end of which is located substantially at the middle of the outer water tubes *c*. At one of these branches *d* is located the superheater *g* of any usual or approved construction. The other branch or conduit *e* contains a damper *h*. In the particular construction illustrated, the superheater at the left of the boiler is contained in the inner branch or conduit, while on the right-hand side of the boiler the superheater is located in the outer branch of the hot gas flue.

When starting the boiler or at such times as only relatively low superheating temperatures is required, the dampers *h* will be placed in their open position. Thus the greater part of the hot gases on each side of the boiler will pass across the water tubes *c* and then up through the branches *e* which contain no superheater and which therefore offer less resistance to the flow of the gases. Only a small portion of the gases will go through the branches *d* in

which the superheaters *g* are arranged. 55 Combustion will thus be promoted but the superheating action will be reduced. During the normal operation, however, a less active generation of steam is desired, with an increase in the heating action at the 60 superheaters *g*. For this purpose the dampers *h* will be closed so that nearly one-half of the heating surface of the boiler at each side thereof will be cut off from steam generation. As the hot gases thus come in 65 contact with only a relatively small portion of the boiler surface, they retain a higher temperature and thus are able to act more effectively on the superheaters *g* than if they enter the branches or conduits *d*. It 70 will be noted that the travel of the gases is always upward in the branches or conduits *d e* whether the dampers *h* are open or closed; that is, there is no reversal of a gas flow when the position of the dampers is 75 changed.

While I have illustrated superheaters on both side of the boiler, it will be readily understood that either one of the superheaters shown may be omitted and, in some 80 cases, such a one-sided arrangement will afford quite satisfactory results. It will also be understood that by adjusting the damper or dampers *h* to different positions, I can regulate, in various ways, the proportion of hot gases flowing through the superheaters and through the open branches *e* respectively, so that the heating action in the superheaters can be regulated with great nicety. 90

I claim:

1. A water tube boiler comprising an upper drum, lower drums, water tubes connecting the lower drums with the upper drum, hot gas flues for directing the combustion gases across said water tubes between the upper drum and the lower drums, partitions sub-dividing said flues into outer and inner branches, said partitions extending downwardly to about the middle portion 100 of said water tubes, superheaters in one branch of each hot gas flue and dampers in the other branches of said flues. 95

2. A water tube boiler comprising an upper drum, lower drums, inclined water tubes connecting said lower drums with the upper drum, hot gas flues for conducting the combustion gases across said water tubes be- 105

tween said upper and lower drums, upright partitions extending in said flues to about the middle portion of the outer water tubes and subdividing said flues into inner and 5 outer branches, superheaters located in one branch of each flue and dampers located in the other branches of said flues.

3. A water tube boiler comprising an upper drum and lower drums, water tubes 10 connecting said lower drums with the upper drum, hot gas flues for conveying the combustion gases across said water tubes, a partition sub-dividing one of said flues into two branches and extending to about the middle 15 portion of said water tubes, a superheater

located in one of said branches and a damper located in the other branch.

4. A water tube boiler comprising an upper drum, lower drums, inclined water tubes connecting said lower drums with said 20 upper drum, hot gas flues for conveying the combustion gases across said water tubes, an upright partition sub-dividing one of said flues into two branches and extending downwardly to about the middle of the 25 outer water tubes, a superheater located in one of said branches and a damper located in the other branch.

PETER THOMSEN.
